UNITED STATES PATENT OFFICE

WILLIAM SCHULTZ AND JAMES ALLEN SCHULTZ, OF JONESBORO, ARKANSAS

SPOT BOARD

Application filed May 31, 1928. Serial No. 281,836.

This invention relates to spot boards which are used on railroad tracks for bringing sections of the track up to grade, for leveling, and for ballasting purposes. The use of spot boards is well known to those skilled in the art, and the present device is intended to function in every instance and for all purposes wherein conventional spot boards are now employed.

10 Objects of the invention are: to provide an improved type spot board; to provide a novel spot board supporting and leveling means; to provide an improved mounting for spot boards in relation to established grade levels; to provide an improved rabbet block sighting assembly for use in connection with the spot board; and to provide a spot board supporting means which is self-sustaining when in operation.

15 With these and such other objects in view as will be apparent from the description, the invention resides in the novel construction, combination and arrangement of parts hereinafter described and claimed and illustrated 20 in the accompanying drawings which show in connection with the specification a preferred embodiment of the principles of our invention.

Figure 1 is a perspective of a spot board 30 constructed in accordance with the principles of the invention and as mounted in operative position relative to track rails and a grade stake.

Figure 2 is an end elevation substantially 35 from the right of Figure 1 and illustrating the spot board in section.

Figure 3 is a vertical section substantially on the line 3—3 of Figure 2.

Figure 4 is a horizontal section substantially 40 on the line 4—4 of Figures 2 and 3.

We have illustrated the spot board as used 45 in connection with a track section having the conventional rails 5 mounted in the usual manner on cross ties 6, the assembly being shown in Figure 1 as mounted substantially at a switch point. The spot board 7 is of the usual configuration of conventional spot boards, but is made longer than the ordinary spot board so that one end may be slidably supported through a receiving yoke member

8 having a socket 9 formed on its bottom face for reception over the top of a grade stake 10 located at one side of the track rails. These grade stakes 10 are a permanent part of the trackway, and are usually located about 55 one hundred feet apart along the track rail and it is from these stakes that the grade levels for the track are established and maintained.

The lower portion of the spot board is 60 preferably painted black, while the upper portion is painted with a distinctive color, preferably white so that a distinctive sight line 11 is formed on each side face of the board for a purpose hereinafter explained. 65 Mounted on the upper edge of the spot board adjacent the end opposite from that which is engageable in the yoke 8, is a spirit level 12 of any suitable type which functions to aid in leveling the spot board in relation to 70 the track grade.

In service the end of the spot board adjacent the spirit level 12 is slidably supported in a substantially rectangular yoke 13 which is suspended by a swivel connection from the lower end of a threaded bolt stem 14, which stem is vertically positioned and operates vertically through a cross head 15 carried at the upper ends of a pair of side arms or uprights 16 having their lower ends flared and secured to a base plate 17, which base plate is elongated and formed with a flat underface 18 for setting engagement over the head of one of the rails 5 as best shown in Figure 1. At opposite sides of the base plate, preferably at each end, depending flanges 19 are provided which function to engage opposite sides of the rail head and maintain the supporting standard in upright position.

The upper end of the stem 14 is preferably 90 formed as an operating crank handle 20 whereby the stem may be manually rotated for operating the spot board when an adjustment is desired in the level thereof. Anchored in any suitable manner, as by manual gripping, within the cross head 15 is a nut 21 through which the stem 14 is threaded so that upon turning movement of the stem 14, the same is raised or lowered vertically for elevating or depressing the spot board when 95

its end is seated within the yoke 13. The upright arms 16 are formed with opposed parallel inner faces 22 which are spaced apart sufficiently to provide a guideway for the yoke 13.

On opposite side faces of the spot board and adjacent the end which is received in the yoke 13, suitable stop members are provided, which in the present instance comprise a pair of angle irons 23, the outturned flange portions of which are adapted to engage against the standards 16 whereby to limit the sliding movement of the spot board and into the yoke 13. If desired, the spot board may be anchored relative to the yoke 13 by means of a cotter pin 24 which is passed through the sides of the yoke and the spot board in the conventional manner. One side face of one of the arms 16, preferably the inner face relative to the trackway, is provided with a scale strip 25 and the upper edge of the adjacent angle iron or stop member 23 is adapted to function as a sliding pointer for cooperation with the scale strip in effecting a reading therefrom. For this purpose we prefer that the top edge of the angle iron 23 be aligned with the sight line 11 on the spot board.

The board is adapted to be used in connection with a pair of rabbet or sighting blocks 26 and 27 which are formed in the conventional manner for seated sliding engagement over the head of one of the rails 5. As in the conventional practice, one of these blocks, the outermost, is of a black color and the inner block 26 is of a distinctive color such as white so that a proper sight may be taken over the level respective tops 28 and 29 of the blocks relative to the sight line 11 on the spot board. In some instances it is desirable to use in connection with the rabbet blocks 26 and 27 an auxiliary spot board supporting block 30 which is adapted to be seated on a rail head under the spot board for supporting the board at a desired height. This auxiliary block is provided with a series of stepped portions 31 whereby the spot board may be seated at any of a number of different levels.

The operation of spot boards is well known to those skilled in the art and need not be specifically referred to herein, it being deemed a sufficient compliance with the statute to state briefly that when it is desired, in one use of the board, to bring a track section up to grade, the spot board is positioned with one end engaged through the yoke member 8 which is seated over the appropriate grade stake 10 and its opposite end is positioned in a movable yoke 13 whereupon by proper manipulation of the stem 14 the spot board is raised or lowered until the desired level is reached as indicated from the spirit level 12. This spirit level being located at the movable end of the spot board is directly

adjacent an operator and this location facilitates speed of operation and accuracy of alignment, necessitating the services of but one operator at the elevating means. The supporting standard with its base plate 17 when placed on a rail head will by reason of the side flanges 19 maintain itself in upright position and therefore the necessity of bracing members is dispensed with. With the spot board properly leveled relative to the established grade as indicated by the grade stake, the outermost rabbet block 27 is positioned on a properly leveled rail section and the inner block 26 is positioned on an intermediate rail section which it is desired to bring up to proper grade. The rail section upon which the block 26 is mounted may then be raised or lowered by suitable jack means until its top 26 sights on a level with the top 28 of the block 27 and the sight line 11 on the spot board. When this point is reached, the track section will be at the proper grade.

While in this embodiment of the invention we have illustrated and described certain specific details entering into the construction and operation thereof, we desire it to be understood that the invention is not to be limited specifically thereto, but that any desired changes and modifications may be made in the details as will fall within the scope of the invention as claimed.

We claim:

1. In a spot board assembly, the combination with a grade stake, of a yoke member having a socket formed therein for seating engagement over the top of the grade stake, a spot board having one end formed for sliding supporting engagement through said yoke member, track engageable means for supporting the opposite end of the spot board, and including means for moving said opposite end of the spot board in a vertical plane.

2. In a spot board assembly, a spot board, a spirit level secured thereto, means for supporting one end of said spot board in a fixed relation relative to a grade stake, a standard, means for mounting said standard over a rail head, a vertically movable stem mounted in said standard, a yoke swiveled on the lower end of said stem for supporting the opposite end of said spot board, and means for retaining the adjacent end of the spot board in engagement with said yoke.

3. In a spot board assembly, a standard comprising a base plate having flanged portions for engagement with a rail head, parallel spaced uprights extending from said base, a cross head connecting the upper ends of said uprights, a vertically movable stem disposed through said cross head and extending between said uprights, a non-traveling nut threaded over said stem within said cross head, a yoke swiveled to the lower end of said stem and disposed between said uprights for

guiding relation thereby, a spot board, means for supporting one end of said spot board within said yoke and including an angle iron member secured to said spot board for a vertically slidable bearing against one of said uprights, said adjacent upright being provided with scale indicia, and said spot board carried member being positioned to act as a pointer in conjunction with said scale indicia.

10 In testimony whereof we affix our signatures.

WILLIAM SCHULTZ.
JAMES ALLEN SCHULTZ.
